UNITED STATES PATENT OFFICE.

WILLIAM M. BATES, WILLIAM C. KNIGHT, AND JOHN M. GAST, OF HUNTSVILLE,
ALABAMA.

CHURN STAND AND POWER.

935,834.

Specification of Letters Patent.

Patented Oct. 5, 1909.

Application filed January 12, 1909. Serial No. 471,991.

To all whom it may concern:

Be it known that we, WILLIAM M. BATES, WILLIAM C. KNIGHT, and JOHN M. GAST, citizens of the United States, residing at 5 Huntsville, in the county of Madison and State of Alabama, have invented certain new and useful Improvements in Churn Stands and Power, of which the following is a specification.

10 Our invention relates to new and useful improvements in churn constructions, and our object is to provide novel and simple means for supporting a churn dasher and operating the same.

15 Further objects and advantages of our present invention will appear in the course of the following description, in which reference is made to the accompanying drawings, forming a part of this specification, and in 20 which,

Figure 1 is an elevation of our improved apparatus. Fig. 2 is a horizontal sectional view taken therethrough on the line 2—2 of Fig. 1. Fig. 3 is an elevation of the supporting arm removed, and, Fig. 4 is a detailed sectional elevation of a portion of the supporting standard, illustrating particularly the connection of the supporting arm thereto.

25 In the practical embodiment of our invention, we mount a supporting standard 1, upon a supporting base 2, which may have depending legs 3, by means of the flanged base 4 of said supporting standard, and bolt 5.

30 The supporting standard 1 is in the form of a double channel beam, as will be seen by particular reference to Fig. 2, and has its web 6 provided with a longitudinally extending slot 7, adjacent its upper end, and 35 provided with a rectangular enlargement 8 at the lower end thereof. The flanged portions 9 along one longitudinal side of the standard 1, are provided, for approximately the length of the slot 7, with a series of 40 transversely alined cut out portions 10, for a purpose hereinafter described.

45 The supporting arm 11, of the dasher and its operating mechanism, is provided with a central strengthening offset 12, and is directly connected at one end to, and extends at right angles to, the supporting standard 1. To this end, a headed bolt 13 is passed through the slot 7 of the standard 1, and through a central opening adjacent one end

of the arm 11, and is threaded for the reception of a wing nut 14 beyond said arm. The arm 11 is provided with transversely extending ribs 15, one upon each side of its opening for the reception of bolt 13, which ribs are adapted for engagement with the inner surface of the flanged portions 9 of said supporting standard, and serving, together with projections 16, centrally thereof, which engage alined ones of the cut out portions 10, to rigidly maintain the arm 11 in the desired position. The supporting arm 11 is provided intermediate its end, with a longitudinal slot 17, terminating at its end nearest the standard 1, in a rectangular enlargement 18, and said arm is further provided upon its outer end with a transverse semi-tubular extension 19, which together with the transverse semi-tubular end 20 of a supplemental arm 21, forms a tubular support for the dasher shaft 22. 55 60 65 70 75

75 The dasher shaft 22, is provided upon its upper end, beyond the tubular support, with a fixed beveled gear 23, and upon its lowest extremity with a circular dasher 24. Said shaft 22 is further provided with a tubular sleeve 25, surrounding the same between its circular dasher 24 and the lower end of the tubular support thereof, and loosely rotatable thereon. Said sleeve 25 is provided upon its upper end, with a beveled gear 26, 80 and upon its lower end with a circular dasher 27 similar to the dasher 24 of the shaft 22. The semi-tubular end 19 of the supporting arm 11, is provided with a central trunnion 28, extending from the outer 85 surface, and adapted for the reception of a beveled gear 29, of a diameter sufficient to bring its geared portion into simultaneous engagement with the beveled gears 23 and 26, of the shaft 22, and sleeve 25, respectively, which beveled gear 29, constitutes the driving wheel and is provided with a crank 90 95 100 105 110 by which the same may be rotated.

To secure the supplemental arm 21 in engagement with the supporting arm 11 as shown, a headed bolt 31 is projected through the slot 17, of said arm 11, and through an opening in the supplemental arm 21, and is provided with a threaded end for the reception of a wing nut 32, by which the said arm 21 may be securely clamped. The supplemental arm 21 is further provided with an angular extension 33, upon one end, which

in the clamped position thereof, projects through the slot 17 of the arm 11, to insure rigidity thereof.

Having fully described our invention, we claim:

A dasher mechanism support of the character described, comprising a vertical I-beam support composed of spaced parallel sides connected by a centrally arranged cross member, said spaced sides being provided with a plurality of alined notches near the upper end thereof, a horizontal supporting arm provided with spaced parallel upstanding ribs upon one side thereof, each of said ribs being provided with at least one laterally and outwardly extending finger, said

horizontal arm being adapted to be secured laterally upon said vertical I-beam support, said spaced upstanding ribs engaging said spaced sides and said lugs fitting within selected notches for rigidly locking said horizontal arm to said vertical beam support and means for maintaining said arm in such locked position.

In testimony whereof we affix our signatures in presence of two witnesses.

WILLIAM M. BATES.
WILLIAM C. KNIGHT.
JOHN M. GAST.
